UNITED STATES PATENT OFFICE.

LEE S. BURRIDGE, DECEASED, LATE OF NEW YORK, N. Y., BY FRANCIS O. BURRIDGE, EXECUTOR, OF NEW YORK, N. Y., ASSIGNOR, BY MESNE ASSIGNMENTS, TO UNDERWOOD TYPEWRITER COMPANY, OF NEW YORK, N. Y., A CORPORATION OF DELAWARE.

TYPE-WRITING MACHINE.

1,322,530.

Specification of Letters Patent. Patented Nov. 25, 1919.

Application filed June 13, 1918, Serial No. 239,796. Renewed April 7, 1919. Serial No. 288,378.

To all whom it may concern:

Be it known that LEE S. BURRIDGE, deceased, late a citizen of the United States, and late residing in the borough of Manhattan, county, city, and State of New York, invented certain new and useful Improvements in Type-Writing Machines, of which the following is a specification.

This invention relates to typewriting machines, and is herein disclosed as applied to a small, portable typewriting machine which shall incorporate substantially all of the advantages of larger machines, and yet, at the same time, may be very light. To make such a machine durable and practical, it is essential that the parts shall be not only light, but rigid, and that the weight of the machine shall be concentrated as far as possible at the point where it is most effective, viz., largely in the neighborhood of the carriage, to absorb the shock of its arrest by the escapement mechanism.

One serious difficulty in the designing of such machines, of the visible writing type, is that the type-bars have to be supported upon a rigidly held segment, which stands in front of the platen, and which must be supported in such a way as not to interfere with the shift-carriage of the machine, or with any part of the traveling carriage. Moreover, the connections between the key-levers and the type-bars put a very considerable strain upon the segment and upon the points of support of such connections.

According to the present invention, the segment may form part of a substantially triangular or tripodod structure set in the main frame of a typewriter, said triangle advantageously having its bottom forming a fulcrum-point for the connections between the key-levers and the type-bars.

The segment forms a truncated top for the triangle, instead of a true apex therefor, and the segment may therefore be further supported by a girder anchored in the bottom member of the triangle, and also anchored in the frame of the machine at one or more other points. To obtain the requisite lightness, this girder may be in the form of a thin, flat plate, so it may be easily stamped out of sheet-metal. The other parts of the triangle may be formed of sheet-metal members having one or more turned-up edges, thus enabling said mem-

bers, although light, to be exceedingly stiff. Moreover, the fulcrum-plate, upon which the key-levers themselves are mounted, may be anchored to the girder, thus forming a rigid structure between the pivot-plate of the key-levers and the fulcrum-points of their connections to the type-bars. By having the aforesaid girder made out of sheet-metal, it is possible to cut it out in such a way that it clears all moving parts with which it might interfere, and yet possesses great strength in the plane of its surface.

Other features and advantages will hereinafter appear.

In the accompanying drawings,

Figure 1 is a diagrammatic sectional side view of a type-writing machine, embodying the present invention. This view for clearness shows a central type-bar, but other parts to the left of the center are also shown.

Fig. 2 is a perspective, side view of the central stiffening girder.

Fig. 3 is a plan view of the machine, illustrating the segment-supporting structure and certain coöperating parts, with most of the other mechanism removed.

In the machine herein disclosed, keys 1 are mounted on the front ends of levers 2, pivoted at their rear ends in a plate 3, which is illustrated as a segment, Fig. 3. Whenever a key 1 is depressed, a cam-follower 4 upon the lever carries down a double cam 5, which is pivoted at 6 on a bracket 7, so that a bell-crank-arm 8, fast to the cam 5, will swing forwardly, drawing downwardly forward a link 9, which is pivotally attached to a type-bar 10, thus swinging said type-bar upwardly and rearwardly against the front side of a platen 11, with the result that a type 12 on the type-bar will print against the platen.

The link 9 is connected to the type-bar 10 by a pivot 13, well behind the hanger-pivot 14, on which the type-bar swings, so that the link 9 is pulled almost forwardly during the swing of the type-bar. The hanger-pivot 14 is in the form of a curved rod, passing through openings 15 in ears 16 of a solid metal segment 17. This segment is inclined rearwardly at an angle of about thirty degrees, to enable the type-bars 10 to spread the types widely, so that a small segment will accommodate a large number of type-bars, thus rendering it possible to re-

duce the size of the machine, and consequently its weight. The segment 17 has faces at its ends substantially radial to the curvature of the segment, and each end is held fast to a thin, metal channel-bar 18, extending downwardly toward the front of the machine from the segment, each channel-bar going to the corresponding side bar 19 of the machine, to which it is firmly held by a screw 20.

Each channel-bar 18 is firmly held to the corresponding face of the segment 17 by means of a screw 20^a and other means, such as a dowel-pin 21. The ends of the channel-bars 18 are bent over, as clearly seen in Fig. 3, so that their lower ends lie flat against the faces of the adjacent side bars 19, and their lower ends may terminate flat against a tie-plate 22, which extends across the bottom of the machine, and to which the brackets 7 are screwed or riveted. The tie-plate 22 is shown in the form of an L-plate having a vertical web 23, and as having its flat web 24 resting on the bottom flanges 25 of the side bars or plates 19,—these side plates being also in the form of L-plates. This structure, it will be observed, furnishes an extremely rigid connection for supporting the pivots 6 and the pivots 14 relatively to each other, thus enabling the great tension of the links 9 to be taken up without putting any strain on the rest of the machine. It will be noted that to bring the channel-bars or plates 18 to the tie-plate 22, the channel-plates 18 are somewhat more nearly horizontal than the segment 17.

To give further rigidity of the mechanism, there is provided a girder 26, (see Fig. 2), which serves to further stiffen the mechanism. This girder 26 is held by screws 27 to the rear plate 28 of the machine frame, which also is in the form of an L-plate firmly secured to the side plates 19. The girder 26 includes a U-shaped portion 29, in the opening of which lies a hollow shaft 30, forming part of the platen-shift mechanism, the remainder of which latter may be substantially identical with that disclosed in application, Serial No. 52,594, filed September 27, 1915. In front of this U-shaped portion, the girder 26 is provided with a horizontal elbow 31, firmly secured or riveted at 33 to a transverse tie-plate 32, Fig. 3. This tie-plate is in the form of an L-plate, held by separated rivets or screws 34 to the bottom flanges 25 of the side plates 19, and comprising an upwardly-turned web 35. Upon this tie-plate 32, the key-lever fulcrum-plate 3 is firmly supported by being screwed against brackets 36, which in turn are firmly screwed or riveted to the bottom of the plate 32. The girder 26 may further support the fulcrum-plate 3, as by resting against it, with an arm 38.

The girder 26 is also so constructed that it furnishes a support for the segment 17 and a connection between the segment and the tie-plate 22. For this purpose, the girder 26 has an upward extension 39 rising 70 from in front of the elbow 31, said extension passing upwardly in front of the fulcrum-plate 3 and having at its upper end two elbows 40, turned at right angles in opposite directions from it, to which is screwed 75 an S-shaped flat channel-plate 41, which extends up over the internal angular surface 42 of the segment, and is there held by screws 43. From the elbows 40, the girder 26 extends forwardly and slightly downwardly (to keep well below the type-bars) 80 to the front L-plate 44 of the machine frame, against which it bears, and to which it may be anchored by a screw 45 passing through the turned-over end 46 of the girder. 85

The girder 26 is connected to the tie-plate 22 by a projection 47 unitary with the girder and extending vertically downwardly therefrom. To hold it firmly to the tie-plate 22, the projection 47 is provided with a 90 turned-up elbow 48, which is screwed or riveted to the tie-plate 22 practically at the center of the machine, thus forming a firm connection between the center of said tie-plate and the center of the segment, with the 95 result that the strain formed by drawing on the links 9 at the center of the tie-plate is thus adequately cared for. In order to give the girder 26 further strength, it is provided with a forwardly-extending lower 100 portion 49 springing from the projection 39, said lower portion being curved downwardly at 50, to permit the insertion of an annular arched plate 51, across which the returning-springs 52 of the key-levers 2 are tensioned. 105 The forwardly-extending portion 49 then curves upward at 53, clearing the connecting rod of the shift-mechanism (not shown) to join the main portion of the girder.

The channel-bars 18 not only serve to 110 support the segment, but they also serve to support the curved type-bar-rest 54, which is in the form of a flat bar having a front segmental portion, covered with an anti-rebound cushion 55, and having ends 56 which 115 extend almost straight rearwardly to the channel-bars 18, to which they are held by rivets or screws 57. The S-shaped channel-plate or bar 41 may be utilized as a steady-ing member for a type-guide 58, which may 120 be in the form of an S-shaped member adapted to fit between the turned-up edges of the S-shaped channel-plate and be held in place by the screws 43, which pass not only through the channel-plate 41, but also 125 through the type-guide 58.

Inasmuch as the segment is supported by the thin, flat channel-bars 18, the segment-supports furnish ample room for the ribbon-mechanism, disclosed in the above-men- 130

tioned application, which is mounted on the front part 59 of the shift-frame, which latter includes, as set forth in said application, the rear track 60 and the front track 61, on which the carriage travels. It also brings the support of the segment entirely clear, and, except for the thin girder 26, entirely in front, of the escapement mechanism, which includes the vibrating bar 62.

10 The escapement mechanism is operated as disclosed in the aforesaid application, by means of a universal bar 63 underlying the key-levers 2, and pivoted on ears 64 of the brackets 36. As disclosed in said application, the universal bar 63 is connected by a link 65 to a rocking member 66, journaled in brackets 67, also mounted on the tie-bar or rod 32, said rocking member 66 rocking in a slightly cut-away portion 68 of the girder 26. The universal bar 63 is tensioned upwardly by springs 69 anchored in the horizontal ends 56 of the type-supporting bar 54.

15 The space-bar 70 is fast on a rock-shaft 71, journaled on brackets 72, extending horizontally from the lower web 24 of the tie-plate 22, and is normally held upward by a spring 73, also anchored in said plate. The space-bar 70 is connected by a link 74, extending 20 from a rock-arm 75 of the shaft 71, and vibrating a rock-arm 76, which supports one end of the vibrating bar 62.

25 The structure brings the heavy segment adjacent the carriage, thus giving inertia to the whole machine at that part. Substantially the remainder of the parts may be stamped of metal, so the whole machine is 30 very light.

35 Variations may be resorted to within the scope of the invention, and portions of the improvements may be used without others.

Having thus described the invention, I claim:

1. In a front-strike typewriting machine, 40 the combination with a segment and a frame including bottom edge plates, of substantially radial ends for said segment, supporting bars fast to said ends and extending to said bottom plates to support the segment 45 therefrom, and a tie-plate extending from one bottom plate to the other adjacent to the ends of said bars.

2. In a front-strike typewriting machine, 50 the combination with a segment and a frame including bottom edge plates, of substantially radial ends for said segment, supporting bars fast to said ends and extending to said bottom plates to support the segment 55 therefrom, a back-bottom plate for said machine, and a girder extending from said back-bottom plate to the segment to support the latter.

3. In a front-strike typewriting machine, 60 the combination with a segment and a frame including bottom edge plates, of substan-

65 tially radial ends for said segment, supporting bars fast to said ends and extending to said bottom plates to support the segment therefrom, a back-bottom plate for said machine, a girder extending from said back-bottom plate to the segment to support the latter, and a tie-plate extending from one 70 bottom plate to the other adjacent to the ends of said bars.

4. In a front-strike typewriting machine, 75 the combination with a segment and a frame comprising bottom L-plates, of channel plates connecting said segment to said bottom plates, so that the segment and the last-named plates form a triangle, and a tie-plate 80 connecting the bottom plates adjacent the ends of the channel plates to complete the triangle.

5. In a front-strike typewriting machine, 85 the combination with a segment and a frame comprising side bottom L-plates, of channel plates connecting said segment to said bottom plates, so that the segment and the last-named plates form a triangle, a tie-plate 90 connecting the bottom plates adjacent the ends of the channel plates to complete the triangle, a back L-plate also forming part 95 of the machine frame, and a girder extending from said back L-plate to support the segment and also extending to said tie-plate and fast thereto.

6. In a front-strike typewriting machine, 100 the combination with a segment and a frame comprising bottom L-plates, of channel plates connecting said segment to said bottom plates, so that the segment and the last-named plates form a triangle, a tie-plate 105 connecting the bottom plates adjacent the ends of the channel plates to complete the triangle, a back L-plate also forming part of the machine frame, a girder extending from said back L-plate to support the segment and also extending to said tie-plate and fast thereto, type-bars mounted in said 110 segment, levers journaled on said tie-plate, links connecting said type-bars and said levers, and keys for operating said levers to draw said links to cause the types to print.

7. In a front-strike typewriting machine, 115 the combination with a type writer frame and a segment inclined to the vertical, of bottom edge plates for said frame, and supporting bars extending from said segment and nearly parallel to its face and anchored in said bottom plates.

8. In a front-strike typewriting machine, 120 the combination with a segment inclined to the vertical and a typewriter frame, of bottom edge plates for said frame, supporting bars extending from said segment and nearly parallel to its face and anchored in said bottom plates, and a tie-plate extending across said machine and connecting said bottom plates.

9. In a front-strike typewriting machine, 125

- the combination with a segment inclined to the vertical and a typewriter frame, of bottom edge plates for said frame, supporting bars extending from said segment and 5 nearly parallel to its face and anchored in said bottom plates, a tie-plate, a back-bottom plate for said machine, and a girder anchored in said back-bottom plate and said tie-plate and supporting said segment.
10. In a front-strike typewriting machine, the combination with a segment inclined to the vertical and a typewriter frame, of bottom edge plates for said frame, supporting bars extending from said segment and 15 nearly parallel to its face and anchored in said bottom plates, a tie-plate extending across said machine and connecting said bottom plates, a back-bottom plate for said machine, and a girder anchored in said back-bottom plate and said tie-plate and supporting said segment.
11. In a front-strike typewriting machine, the combination with a back-bottom L-plate, of side bottom L-plates, a front plate, an 25 L-tie-plate extending between said side plates intermediate the front and back of the machine, a segment, channel plates rising from said side plates adjacent said tie-plate and united to the segment to form a triangular structure with the segment at the apex, and means for supporting said segment from the back L-plate.
12. In a front-strike typewriting machine, the combination with a segment and a frame 35 for the typewriter, means for supporting said segment from the sides of the frame, a back plate, a girder extending from said back plate to the segment, an extension of the girder forming a channel plate by which 40 it engages the segment, and a type-guide having a lower extension lying within the channel plate adapted to form part of a locking means for locking the girder to the segment.
13. In a front-strike typewriting machine, the combination with a segment, of plates supporting it from the sides of the machine, so that the segment forms substantially a 50 triangle therewith, a girder extending forwardly and backwardly of the machine also supporting the segment, and means whereby the girder is supported both in front of and behind the segment.
14. In a front-strike typewriting machine, 55 the combination with a segment, of plates supporting it from the sides of the machine, so that the segment forms substantially a triangle therewith, a girder extending forwardly and backwardly of the machine also 60 supporting the segment, a support for said girder at the back of the machine, a tie-plate between the sides of the machine in which the girder is anchored, type-bars, operating devices for the type-bars mounted upon said tie-plate, and links connecting said operat- 65 ing devices and said type-bars for operating them.
15. In a front-strike typewriting machine, the combination with a segment, of plates supporting it from the sides of the machine, 70 so that the segment forms substantially a triangle therewith, a girder extending forwardly and backwardly of the machine also supporting the segment, a support for said girder at the back of the machine, a tie-plate between the sides of the machine in which the girder is anchored, type-bars, operating devices for the type-bars mounted upon said tie-plate, links connecting said operating devices and said type-bars for 75 operating them, an extension of said girder in the front of the machine, and a front plate of the frame adapted to support the girder at the front.
16. In a front-strike typewriting machine, 80 the combination with a segment and a frame having bottom side plates and a back-bottom plate, of supports for said segment rising from said bottom plates, so that the segment forms the apex of a pyramid having its supports in the side plates and the back plate.
17. In a front-strike typewriting machine, 85 the combination with a segment and a frame comprising side plates and a back plate, of supports for said segment extending to said side plates, a tie-plate extending across the machine between said supports, a girder for supporting said segment anchored in the rear plate, a second tie-plate extending 90 across the machine to which the girder is anchored, key levers, a fulcrum for said key levers on said second-named tie-plate, type-bars journaled in the segment, operating devices for said type-bars on the first 95 tie-plate, links extending from said operating devices to said type-bars, and connections from the key levers to the operating devices.
18. In a front-strike typewriting machine, 100 the combination with a segment and a frame comprising side plates and a back plate, of supports for said segment extending to said side plates, a tie-plate extending across the machine between said supports, a girder for 105 supporting said segment anchored in the rear plate, a second tie-plate extending across the machine to which the girder is anchored, key-levers, a fulcrum for said key-levers on said second-named tie-plate 110 type-bars journaled in the segment, operating devices for said type-bars on the first tie-plate, links extending from said operating devices to said type-bars, connections from the key-levers to the operating devices, and an escapement mechanism comprising vibrating parts mounted on and tensioned from said second tie-plate.
19. In a typewriting machine, the combination with a frame, of a bottom cross- 115 120 125 130
